UNITED STATES PATENT OFFICE.

JOHN W. LANDRUM, OF LYNCHBURG, VIRGINIA, ASSIGNOR OF ONE-THIRD TO SAMUEL C. WHITLOW AND ONE-THIRD TO EDWARD T. DANCE, BOTH OF LYNCHBURG, VIRGINIA.

ADJUSTABLE BOX FORM FOR WRAPPING MACHINES.

Application filed May 2, 1925, Serial No. 27,478. Renewed February 25, 1926.

To all whom it may concern:

Be it known that I, JOHN W. LANDRUM, a citizen of the United States, residing at Lynchburg, in the county of Campbell and State of Virginia, have invented certain new and useful Improvements in Adjustable Box Forms for Wrapping Machines; and I do hereby declare the following to be a full, clear, and exact description of the invention, such as will enable others skilled in the art to which it appertains to make and use the same.

This invention relates to a box for use on wrapping machines, and it generally aims to provide a novel construction which is adjustable, so that the machine will be adapted for work in connection with boxes, tops or the like, differing in size, to thereby increase the range of usefulness of the machine.

Another object is to provide a novel construction wherein various parts are supplied in different sizes and are arranged interchangeably to accomplish the end stated.

Additional objects and advantages will become apparent from a consideration of the description following taken in connection with accompanying drawings illustrating an operative embodiment.

In said drawings:

Figure 1 is a view in side elevation illustrating the invention in connection with associated parts of the box wrapping machine;

Figure 2 is a plan view of the form;

Figure 3 is a horizontal sectional view taken through the parts of the form and on a line with one row of the dowel rods;

Figure 4 is a side elevation of the holder;

Figure 5 is an end elevation of the holder;

Figure 6 is a longitudinal central sectional view;

Figure 7 is an inverted plan view;

Figure 8 is a perspective view from above of the center panel;

Figure 9 is a perspective view of one of the corner blocks, and

Figure 10 is a perspective view of one of the intermediate blocks.

Referring specifically to the drawings, the form is shown generally at 10 and is used for instance in a box wrapping machine such as that of the "Stokes and Smith" type, the form being adapted to fit the box for coac-

tion during the gluing or pasting of an ornamental wrapper thereon. The holder is removably carried by a plunger rod 11 adapted for depression or vertical movement in any suitable manner.

Carrying out the invention, lower corner blocks are provided as at 12 each having a round vertical opening 13 therethrough whereby the device is slidably mounted on guiding elements 14 of the machine, which are adjustable to vary the distance between them lengthwise and transversely of the machine so as to accommodate different adjustments of the form. At the sides and ends, intermediate blocks 15 are provided between the corner blocks. The intermediate blocks 15 at their sides and bottoms are intact through the provision of walls 16 and 17, respectively, and at their ends have bearings 18 in which dowel rods 19 are rigidly secured, and which project beyond the outer ends of said bearings 18. The projecting ends of said rods 19 or pins, extend removably into openings 20 provided in two ends of the corner blocks 12. The rods 19 are preferably arranged in a vertical row of two, that is one over the other as shown. Threaded in each block 12, is a screw 21 adapted for binding against the uppermost of the dowel pins or rods 19 to thereby secure the end blocks and intermediate block 15 together against relative movement. These screws are of any suitable type but preferably have square or other sockets 22 therein adapted to be fitted by a wrench in order to effect the turning thereof.

The under surfaces of the blocks 12 adjacent the inner corners are recessed as at 23 and entering said recesses and filling the entire space at the lower surface of the block 12 is a supporting panel 24. The under surface of this panel is flush with the under surfaces of the blocks 12 and 15. Detachable connected to the panel 24 as by screws 25, is an attaching post 26, adapted for detachable connection to the plunger 11, as by means of a set screw or the like 27.

The block is braced and rigidified by bars 30, one at each end thereof, slotted at their ends as at 31, to accommodate fastening screws 32 which enter suitable threaded openings in the corner blocks 12. In saddled relation to the bars 30 is a bar 33 having a central depressed portion 34 pro-

vided with an opening 33^a through which the post 26 snugly extends. The ends of bar 33 are slotted as at 35 and screws 36 pass therethrough and enter screw threaded openings 37 in the bars 30. The structure is braced and rigidified by the bars 30 and 33 and the post 26 is particularly steadied by the bar 33.

In a complete outfit, all of the parts except the set screws and the corner blocks, are made in pluralities and each one in different sizes, so that they may be matched and connected together to form forms of different sizes, to the end that the same may be used in connection with different sized boxes or tops and at the same time, will have their sides and ends and under surface closed. It will be understood of course that in all sizes, the dowel pins or rods 19 will be of the same size so that they may enter the openings 20 of the corner blocks. Also, the shank or post 26 need not be made in a plurality, since with it being detachable, it may be applied to various sized panels 24.

In using the device, it will be understood that the appropriate parts are selected and connected together as shown in the drawings and that when a different sized box is to be operated upon, different sized intermediate blocks 15, panel 24 and bars 30 and 33 may be used to provide such size.

Various changes may be resorted to provided they fall within the spirit and scope of the invention.

What is claimed is:—

1. A device of the class described comprising a panel, corner blocks disposed thereon, intermediate blocks between the corner blocks, bars connecting the corner blocks, a bar in saddled relation to the first mentioned bars, and a fastening element for the panel extending through the last mentioned bar.

2. A device of the class described comprising corner blocks, intermediate blocks, said intermediate blocks having bearings at their ends, dowel pins mounted by the bearings and extending beyond the same, said corner

blocks having openings removably receiving the dowel pins, and means supporting said blocks and closing the space between them at the bottom. 50

3. A device of the class described comprising corner blocks, intermediate blocks, said intermediate blocks having bearings at their ends, dowel pins mounted by the bearings and extending beyond the same, said corner blocks having openings removably receiving the dowel pins, means supporting said blocks and closing the space between them at the bottom, and securing elements carried by the corner blocks engageable with the dowel members. 55

4. A device of the class described comprising corner blocks, intermediate blocks, said intermediate blocks having bearings at their ends, dowel pins mounted by the bearings and extending beyond the same, said corner blocks having openings removably receiving the dowel pins, means supporting said blocks and closing the space between them at the bottom, said corner blocks being recessed at their under surfaces to accommodate said means, a fastening element extending from said means, and means bracing said fastening element and secured to the blocks. 60

5. A device of the class described comprising corner blocks having openings therethrough adapted for coaction with guiding elements, intermediate blocks having bottom and side walls and bearings at their ends, dowel members mounted in said bearings and extending removably into the corner blocks, fastening elements for said dowel members carried by the corner blocks, the inner corner portions at the lower surface of the corner blocks being cut away, a panel extending into said cutaway portions, an attaching post detachably connected to said panel, bars fastened to the corner blocks, 70 and a bar through which said attaching member passes straddling the first mentioned bars and being secured thereto. 75

In testimony whereof I affix my signature.

JOHN W. LANDRUM.
